Application May 25, 1950, Serial No. 164,172

14 Claims. (Cl. 139—231)

1

This invention relates to weft replenishing looms and it is the general object of the invention to provide improved means for revoking a previously called bobbin transferring operation if the shuttle is improperly placed to receive a bobbin.

Multicolor weft replenishing looms generally employ a reserve bobbin magazine including in its construction a setting shaft positively connected to a shuttle position detector, a transerrer latch moved positively by the shaft in one direction only, namely, toward transfer position, and bobbin releasing and shaft setting members having an initial setting without moving the shaft when weft exhaustion is indicated and subsequently having a second or setting motion to rock the shaft and cause it to move the detector to shuttle detecting position and the latch into the path of the lay. If the shuttle is properly placed bobbin transfer occurs normally with the lay and latch mutually engaged for a period starting before and continuing after front center until the lay in its rearward motion moves away from the latch. The lay when approaching front center engages the detector and moves it back to its normal position, thus returning the shaft to its normal position to reset the magazine during the period of engagement of the lay and latch.

If the shuttle is misplaced and engages the detector as the lay beats up the shaft is reset earlier in the loom cycle before the lay reaches a position where the aforesaid period could start. Under these conditions it would be desirable to have a positive connection between the detector and latch to move the latter promptly out of the path of the lay, but since the transerrer latch is always engaged with the lay at front center during a replenishing operation, and this is the normal time for resetting, it has not been possible in the past to establish a positive connection between the usual shuttle position detector and the transerrer latch. Such connections as have been used merely remove a support which holds the latch in transfer position to permit it to fall with the expectation that it will drop out of the path of the lay. The latch does not always move fast enough, however, to clear the lay, with the result that weft replenishing operations sometimes occur when the shuttle is improperly placed, in which event either the bobbin or shuttle will be damaged.

Weft replenishing looms of the type to which the invention more particularly relates ordinarily have the weft feeler at the magazine end and the replenishing operation occurs in a two-pick

2

cycle. If indication of weft exhaustion is given at the beginning of the first pick of the cycle a controller interrupts the normally idle downward motion of an actuator lever floating on an actuator and causes the lever, acting in conjunction with a so-called color slide, to raise one of the previously mentioned setting members to give the magazine an initial setting. The actuator is controlled by a cam which in the past has been made with an area which gives the actuator its full downward motion immediately after the weft feeler has had time to detect the condition of weft and when the lay is in the latter part of the same range of motion it has during the aforesaid period of lay and latch engagement.

The shuttle is then picked to the opposite end of the loom and before it returns to the magazine end the cam, acting through the actuator, causes the lever and color slide to give the previously raised setting member a return or setting motion which moves the shaft to transfer position, thus giving the magazine its complete setting for transfer. This complete setting is effected by another part or area of the cam in the second pick of the cycle.

It is an important object of the present invention to modify the operation of previously known multicolor weft replenishing mechanisms by delaying completion of the down motion of the actuator on detecting beats of the loom until after the lay in its rearward motion from front center has reached the point which it occupies when the dagger on the lay becomes disengaged from the latch on a weft replenishing beat of the loom, and utilize this delayed down motion to reset the magazine later than heretofore and at a time when the latch is free to respond to a force exerted on it positively by the shaft as the latter is returned or reset to its normal position. This result is accomplished by changing the first cam area already mentioned in either of two ways as set forth hereinafter so that it causes the actuator to complete its down motion later than has been common practice heretofore. With this change in the cam it is possible to use the previously mentioned positive connections to the latch and a slight amount of movement of the shuttle position detector by a misplaced shuttle will suffice to move a transfer latch positively out of the path of the lay and prevent an undesired replenishing operation.

The weft feeler operates when the lay is on front center, but the actuator as set forth herein cannot give the magazine its initial setting until the lay has moved rearwardly an appreciable dis-

tance greater than has been common practice heretofore. It is a further object of the invention to provide for holding the indication of the weft feeler until the actuator can move to utilize the indication. In the preferred form of the invention this is accomplished by giving the actuator a preliminary down motion which is just sufficient to effect cooperation or non-cooperation, as the case may be, between the actuator lever and the controller, after which the actuator will dwell briefly and then have its completed down motion which is preferably larger than its preliminary motion. The area of the cam which is in control of the actuator during this operation has a slight decline to produce the first preliminary down motion of the actuator, a dwell following the slight decline, and then a larger decline which completes the down motion of the actuator.

When an electrical weft feeler is utilized, as in the modified form of the invention, provision is made for retaining the indication of weft exhaustion by a holding circuit until it can be utilized by the actuator lever. The holding circuit may be opened by some part of the magazine which preferably does not have a regularly recurring motion, such as the color slide, when it is lifting one of the setting members. In this modified form the entire down motion of the actuator associated with weft detection can be accomplished by a simple cam decline corresponding approximately to the second decline of the preferred cam.

In order that the invention may be clearly understood reference is made to the accompanying drawings which illustrate by way of example two embodiments of the invention and in which:

Fig. 1 is a vertical transverse section of part of a weft replenishing loom having the preferred form of the invention applied thereto looking toward the reserve bobbin magazine and showing the parts in normal position with the lay on front center,

Fig. 2 is a front elevation on an enlarged scale looking in the direction of arrow 2, Fig. 1,

Fig. 3 is a detailed plan looking in the direction of arrow 3, Fig. 1, the rod connecting the setting shaft and shuttle detector being shown in cross section,

Fig. 4 is a detail plan looking in the direction of arrow 4, Fig. 2,

Fig. 5 is a detailed side view looking in the direction of arrow 5, Fig. 2,

Figs. 6, 7 and 8 are diagrammatic views showing the actuator, the preferred form of two-pick cam, and certain of the parts associated with them in different positions,

Fig. 10 is a view similar to Fig. 4 but showing the modified form of the invention,

Fig. 11 is a view similar to part of Fig. 1 showing the normally closed switch which is opened by the color slide to break the holding circuit used with the modified form,

Fig. 12 is a view similar to Fig. 9 but showing the cam used with the modified form, and

Fig. 13 is a diagram of the electric circuit used with the modified form.

Referring to Figs. 1 and 2, a loom frame 1 supports top and bottom shafts 2 and 3, respectively, connected by gears 4 and 5 which are in such ratio that the bottom shaft rotates once for every two rotations of the top shaft. The latter shaft reciprocates the lay L in a back and forth direction between front and

back center positions once for each pick or beat of the loom. The lay, which is shown in its extreme front center position in Fig. 1, has a shuttle box 6 to receive a shuttle S and is provided with a bunter 7.

Secured to the loom frame 1 is a multistack reserve bobbin magazine M which in the present instance can accommodate four vertical stacks of reserve bobbins (not shown). Vertical bobbin releasers or setting members 10, 11, 12 and 13 are mounted on the magazine M for vertical reciprocation. Each releaser is associated with a bobbin controlling cradle a part of one of which is indicated at 14. Each releaser or setting member 10-13 is provided with top and bottom lugs 15 and 16, respectively, for cooperation with a color slide designated generally at 17. This color slide includes a shaft 18 slidably mounted horizontally on the magazine M under control of a positioning lever 19 connected to some part of the loom moving in timed relation with the shifting shuttle boxes (not shown) at the opposite end of the loom.

Secured to shaft 18 is a casting 20 having front and back lifter and depressor fingers 21 and 22, respectively, which register one at a time with the releasers 10-13, depending upon the position of lever 19. A lever 25 mounted for pivotal movement on rod 18 is the means by which the color slide is rocked for the purpose of raising and lowering the releasers 10-13. The lever 25 is connected by depending rod 26 to the left end of a floating operating or actuator lever 27 pivoted as at 28 to an actuator 29. The latter reciprocates vertically in a stationary guide 30 and is connected at its bottom to an actuator rod 31 the lower end of which is pivoted to a cam lever 32 rockable about a stationary pivot 33. As viewed in Fig. 1 the rear end of lever 32 has a roll 34 which fits into a groove 35 of a cam designated generally at C. The cam is secured to and rotates with the bottom shaft 3 in a two-pick cycle.

A mechanical weft feeler mechanism F detects the condition of weft on alternate beats of the loom when the shuttle S is in the box 6 and the lay is at or near its front center position. This feeler cooperates with an arm 36 secured to a rock shaft 37 mounted in a stationary stand 38. The left end of rock shaft 37 as viewed in Fig. 2 has secured thereto an upstanding arm 39 pivoted to the forward end of a controller pin 40 slidably backwardly and forwardly in the stand 38 to occupy two different positions with respect to the right end 41 of lever 27. This end of lever 27 is guided for up and down motion in a vertical slot 42 in stand 38. A torsion spring 43 acts on shaft 37 in a direction tending to move the controller pin 40 rearwardly, or to the left as viewed in Fig. 1, under lever 27.

The weft feeler F has an upright lug 44 for engagement by a stud 45 on transfer mechanism designated generally at T. The transfer mechanism includes an arm 46 pivoted on a stationary stud 47 and having depending arms or fingers 48 to which is pivoted a transfer latch 49 swingable about a pivot 50 on the arms 48.

Mounted for rocking movement in the upper part of the magazine is a setting shaft 55 having secured thereto a casting 56 formed with a shelf or bar 57 which extends horizontally for cooperation with the setting members 10-13. Secured to shaft 55 is an arm 58 carrying a

swivel block 59 slidable in a slot 60 on a yielding block lever 61 rockable about a stationary stud 62. A compression spring 63 operatively interposed between lever 61 and swivel 59 serves to hold the setting shaft 55 and bar 57 yieldingly in either of two positions as determined by stop screws 64. As shown in Fig. 2 the shaft 55, bar 57 and spring lock are in their normal positions.

The upper end of each setting member has pivoted thereto a dog 65 acted on by a compression spring 66 interposed between the dog and the top of the member. A spring plunger 67 cooperates with each releaser to hold the latter yieldingly either in its normal down position or in its raised position when the magazine is given an initial setting incident to indication of weft exhaustion by the weft feeler F.

A shuttle position detector 70 is secured as at 71 to a carrier 72 pivoted on a stationary stud 73 and having an arm 74 pivoted as at 75 to the lower end of a rod 76. The upper end of the latter rod is pivoted to an arm 77 secured to the rear end of the shaft 55. The back 78 of the shuttle box has a slot 79 which registers with the detector 70 to permit the latter to remain down as the lay beats up when the magazine is set for a transfer operation. The purpose of the shuttle position detector 70 is to revoke a previously called replenishing operation in the event that the shuttle S is improperly placed to receive a bobbin.

When the parts are shown in Figs. 1 and 2 and the weft feeler indicates ample weft in the shuttle being detected it will be moved forwardly and move controller pin 48 forwardly out of the path of end 41 of lever 27. The latter will then have an idle down motion as the actuator 29 descends from its neutral position, as will be more fully set forth hereinafter. If, however, the weft feeler indicates weft exhaustion the shaft 37 will not be moved and controller pin 48 will remain under lever 27 to become a pivot around which the actuator lever turns to depress rod 26 and rock the color slide in a counter-clockwise direction, Fig. 2, to engage the top lug of the releaser or setting member registered therewith and lift the latter for an initial setting of the magazine. When a releaser rises its dog will turn in a clockwise direction as viewed in Fig. 2 to overhang the bar 57.

The initial setting of the magazine occurs during the first pick of the two-pick cycle of the actuator without causing angular motion of the setting shaft 55. On the next pick of the cycle, the actuator will rise from its mid position and end 41 of lever 27, being held down by a pin 68 stationary in stand 38, will cause rod 26 to rise to rock the color slide in the opposite direction to lower the raised setting member, provided there has been no change of shuttles at the opposite end of the loom. As the setting member is lowered or returned to its normal position its dog engages bar 57 and rocks the setting shaft 55 in a clockwise direction, Fig. 2, to lower the shuttle position detector to its detecting position by a force transmitted through rod 76. At the same time a bobbin is released from the associated bobbin stack, and the latch 49 will rise into the path of bunter 7 as will be described hereinafter. If in the foregoing operation a different shuttle had returned to the magazine end the color slide would have

moved out of register with the raised setting member, but upon return of the empty shuttle the raised setting member would be lowered in the second pick of a two-pick cycle.

5 The matter thus far described, except as noted in the description to follow, is of common construction and operates in the usual two-pick cycle wherein initial setting of the magazine occurs in the first pick of the cycle and the completed setting occurs in the second pick.

As has already been stated, when the magazine is fully set for a replenishing operation, a bobbin will be transferred if the shuttle is properly placed in the shuttle box, but if the 15 shuttle is misplaced it will raise the shuttle position detector 70 to rock the shaft 55 to reset it to its normal position and thereby revoke the transferring operation. In the past this revoking operation has not been entirely satisfactory for reasons already mentioned.

In carrying the present invention into effect the transerrer latch is positively connected to the setting shaft 55 by means of a rod 80 pivoted at 81 to a part of the latch forward of the latch 20 pivot 59. The upper end of rod 80 is pivoted at 82 to a head 83 pivoted at 84 to an arm 85 secured to shaft 55. Normally this rod 80 will be raised as shown in Fig. 2, but when shaft 55 is rocked to its transfer position by downward motion of 30 one or another of the setting members 19-13 the rod 80 will be lowered and the latch 49 will be lifted into the path of the bunter 7 at a time when the lay is a considerable distance behind the front center position. If the shuttle is misplaced it 35 lifts the shuttle detector 70 as the lay beats up and lifts rod 76 to reset shaft 55 to its normal position. Rod 80 is thereupon lifted to rock the transerrer latch 49 down out of the path of the bunter 7 by a positively acting force. By this 40 positive connection between the shuttle detector, the shaft 55, and the latch 49, assurance is given that a replenishing operation will be prevented by a small amount of upward motion of the shuttle detector 70 when the latter is engaged by a 45 misplaced shuttle.

If the called replenishing operation is not revoked but proceeds in normal manner the bunter 7 and latch 49 will be in mutual engagement for a period of lay motion starting during the latter 50 part of a two-pick cycle when the lay is moving forwardly and continuing into the first pick of the next two-pick cycle until the lay on its rearward stroke pulls the bunter away from the latch. The lay is on its front center position during this 55 period, and resetting of the top shaft 55 and the accompanying return of the shuttle detector and latch to their normal positions must be delayed until after the aforesaid period of engagement between the bunter and latch. This delay is 60 accomplished in the preferred form of the invention by the cam C.

The cam C has two areas A and B, separated by dwells D1 and D2. Area A is in control of the actuator 29 during part at least of the first pick of a two-pick cycle starting when the weft feeler has a weft detecting operation, dwell D1 holds the actuator stationary in mid position for an interval in which lever 19 can shift the color slide if required to do so, area B controls the actuator during part of the second pick of the cycle, and dwell D2 again holds the actuator stationary in mid position at the end of the cycle. Cam C turns in the direction of arrow n, Fig. 9, and its halves P1 and P2 correspond, respectively, to the 70 first and second picks of the two-pick cycle.

Area A includes a preliminary decline *a* followed by a dwell *b* which in turn is followed by a second or completed decline *c* preferably deeper or larger than decline *a*. A return incline *d* leads from decline *c* to dwell *D1*. Area B has an operating incline *e* leading from dwell *D1* to a return decline *f* ending at dwell *D2*. The latter dwell is not very important and can be omitted, but dwell *D1* is significant, although it need not be longer than is sufficient to hold the actuator 29 in its mid or neutral position while the color slide shifts its registry relatively to the vertical setting members 10-13. In the past cams for the actuator have had dwells similar to dwell *D1* except that they were longer than necessary. The decline *a*, dwell *b*, and larger decline *c* are the important parts of area A in the preferred form of the invention, and the other parts of cam C may be as usual except for the shortened length of dwell *D1*.

At the start of a two-pick cycle with the shuttle in the box 6 and the lay on front center the weft feeler F will detect the condition of weft in the shuttle and will determine the position of controller pin 40. At this time decline *a* of area A comes into control of the replenishing mechanism and causes a slight preliminary down motion of the actuator 29 from the position shown in Fig. 6 to that shown in Fig. 7. If the weft feeler has indicated presence of ample weft controller pin 40 will be forward of slot 42 and the actuator during this first preliminary down motion will move the actuator lever 27 to the full line position shown in Fig. 7 behind pin 40 to prevent it from returning to a position under the lever. Dwell *b* holds the actuator and lever 27 in the full line position of Fig. 7 until the lay in its backward motion has reached at least the point at which the bunter 7 becomes disengaged from the latch 49 subsequent to a weft replenishing operation. Decline *c* then comes into control of the actuator 29 and gives it a completed down motion to the position shown in Fig. 8, the pin 40 not having any effect on this normally idle motion of lever 27. The return incline *d* then lifts the actuator to its mid position, as in Fig. 2, and dwell *D1* takes over control of the actuator. These operations effected by area A occur during the first pick of the two-pick cycle.

As the cam continues to turn area B will move lever 27 as already described, but since the feeler has not indicated weft exhaustion no releaser or setting member 10-13 will be raised. The various movements of the actuator occur at regularly recurring two-pick intervals.

If the detector gives indication of weft exhaustion at the start of a two-pick cycle then controller pin 40 will remain under the right end 41 of lever 27 and as the actuator 29 has its short preliminary down motion lever 27 will rock to the dotted line position shown in Fig. 7. This may effect a slight but inconsequential upward motion of the setting member 10-13 registered with the color slide. Lever 27 will remain in the dotted line position of Fig. 7 until the actuator starts its completed down motion, at which time lever 27 will move to the dotted line position, Fig. 8, and the releaser member registered with the color slide will be raised to initiate a weft replenishing operation. In the next pick of the cycle area B will complete the setting of the magazine for transfer, after which the lay as it moves forwardly will engage the transerrer latch and remain in engagement with it for the previously mentioned period of lay motion.

The latter part of the period of engagement

between the bunter and the latch continues into the next two-pick cycle of the cam C and dwell *b* is of such length that it will remain in control of roll 34 until the end of the period. From this it will be seen that the greater part of the down motion of the actuator 29 occurs at regularly recurring two-pick intervals when the bunter is too far behind front center to be able to engage the latch and at times when the latter will be free to respond to any force exerted upon it from the top or setting shaft 55.

As thus far described the shuttle position detector will be in its down or transfer position and the latch will be raised in its transfer position because of the fact that shaft 55 is still locked yielding in its transfer or set position. It is necessary that the magazine be reset before the lay next reaches its front center position, otherwise the transerrer arm will be operated again and prevent the feeler F from giving indication of weft exhaustion if such indication should be necessary due to presence of another shuttle in box 6. The resetting mechanism is shown more particularly in Figs. 1, 2 and 6 to 8.

Extending laterally from the actuator 29 is an arm 98 pivoted at 91 to the lower end of a resetting rod 92 the upper end of which is formed with a slot 93 into which extends a stud 94 on an arm 95 secured as at 96 to the setting shaft 55.

When the actuator 29 is in its neutral position and the magazine is in its normal unset position the slot 93 and stud 94 will be positioned with respect to each other as shown in Fig. 2, and as the actuator moves down for its preliminary motion the rod 92 will descend slightly, and as the actuator has completed its down motion the rod 92 will descend still farther. At this time the stud 94 will be near the top of the slot 93, but preferably not in actual engagement with the upper end of the rod 92. As the actuator 29 returns to its normal or neutral position and is then raised by area B rod 92 will rise and the bottom of slot 93 will approach stud 94, but the latter will not be engaged by the rod. These are the operations of the slot and stud when the magazine is in normal condition.

When the magazine is given its completed setting for a replenishing operation shaft 55 rocks to raise stud 94, but at this time the actuator 29, rod 92 and slot 93 are also rising. When the actuator returns to its mid position slot 93 descends until the top or rod 92 is spaced slightly above the raised stud 94, about as shown in Fig. 7. As the actuator has its next down motion, particularly the part due to cam decline *c*, the upper end of rod 92 will move the stud 94 down, see Fig. 8, and thus return the setting shaft 55 to its normal position to effect return of shuttle detector 70 to its normal raised position and return of the latch to its normal down position out of the path of the lay. This resetting does not occur until after the latch is disengaged from the bunter.

Some weft replenishing looms of the type already described employ a form of weft feeler in which the controller pin 40 is normally out of the path of the right end 41 of the actuator lever 27 and is moved into the path of the latter only upon indication of weft exhaustion. When a feeler of this type is used and indicates weft exhaustion the preliminary down motion of the lever 27 caused by decline *a* will cause the lever 27 frictionally to hold the rear end of the pin 40, after which initial setting of the magazine is effected when area *c* effects completed down

motion of the actuator. Weft detectors operated in this manner may be either mechanical or electrical, the electrical type operating with a solenoid controlling the pin 40 and the solenoid being energized only when indication of weft exhaustion is given.

Electrical weft detectors, however, need not necessarily be used with the cam decline *a* and dwell *b*, since the delay between indication by the feeler and down motion of the actuator can be effected electrically, as by a holding circuit. The modified form of the invention is adapted more particularly to an electrically indicating weft feeler operating with a holding circuit, whether the feeler be electro-mechanical or of the usual two-prong type. In this modified form the cam for the actuator is somewhat simpler than the cam used with the mechanically indicating feeler used in the preferred form.

Referring particularly to Fig. 10, a controller pin 100 will normally be forward of the path of the actuator lever 27 and will be controlled by a solenoid 101 normally deenergized but effective when energized to move the controller pin under lever 27.

The casing 20 of the color slide will have the usual bar 102 formed as part thereof to have sliding relation with respect to the lever 25. A normally closed electric switch 103 has an operating arm 104 for engagement with the bar 102 to open the switch when the color slide rocks to initiate a replenishing operation. Switch 103 may be mounted on a small stand 105 secured as at 106 to some stationary part of the magazine M, see Fig. 11.

The cam C1 will be made as indicated in Fig. 12 and the parts D1, *e*, *f* and D2 thereof may be the same as in cam C. Cam C1, however, has a third dwell D3 which takes over control of the actuator at the start of a two-pick cycle and is in effect a continuation of the dwell D2. As shown in Fig. 12 dwell D3 is a part of area A1. The remainder of area A1 includes a single decline *g* and a return incline *h*. The dwell D3 maintains the actuator 29 stationary until the lay in its rearward motion reaches a point corresponding to the end of the aforesaid period of engagement between the lay bunter and latch, after which the decline *g* moves the actuator down with a single stroke. In effect, the decline *g* and incline *h* may be similar to corresponding parts of previously used cams on multi-color weft replenishing looms except for their location which in this modified form of the invention causes them to come into control of the actuator 29 later in the two-pick cycle than in former practice. As in the preferred form, the two halves P1 and P2 of cam C1 correspond to the first and second picks, respectively, of the two-pick cycle of the modified cam.

Fig. 13 shows diagrammatically the electric circuits which can be used with the modified form of the invention, the weft feeler 119 being shown as of the two-prong type to cooperate with a ferrule 118 on the bobbin when the latter is depleted of weft. It should be understood, however, that the invention will operate with other types of electrically indicating weft feelers and it will be sufficient if the feeler closes a detecting circuit when the depleted shuttle is at the magazine end and the lay is at front center.

As long as ample weft is present the weft feeler will not indicate and pin 100 will remain out of the path of the lever 27. When the weft feeler indicates weft exhaustion it will close the feeler

circuit as follows: Ground G, wire 112, weft feeler 110, wire 113, relay 114, wire 115, normally closed electric switch 103, wires 116 and 117, secondary 118 of an electric transformer T, and wire 119 back to the ground. This circuit will be closed when the lay is at front center and the cam lever roll 34 is in a position approximately between dwells D2 and D3 at the beginning of pick P1 of a two-pick cycle.

When the relay is energized it closes two contacts 120 and 121, the first of which closes the following holding circuit: Ground G, wire 122, contact 120, wire 123, and thence through the relay, switch 103, and transformer back to the ground. This holding circuit maintains the relay energized after the lay moves rearwardly from front center and the shuttle is no longer able to keep the detector circuit closed.

Closure of contact 121 will close the following 20 solenoid circuit: Ground, wire 125, solenoid 101, wire 126, contact 121 and thence through the transformer back to the ground. This solenoid circuit will be closed as soon as the relay responds to closure of the detecting circuit and will 25 remain closed to hold pin 100 under lever 27 as long as the relay holding circuit is closed. These 30 three circuits will be closed at about the time the cam lever roll 34 enters the dwell D3, and the holding and solenoid circuits will remain closed until switch 103 is opened. As the decline 35 *g* takes over control of the actuator 29 the latter will descend to give the magazine an initial setting when the lay in its rearward motion has passed beyond the point where the bunter 7 can 35 possibly engage the latch 49.

Near the end of the rocking motion of the color 40 slide caused by lever 27 as decline *g* lowers actuator 29 the bar 102 will engage arm 104 and open the normally closed switch 103, thereby opening 45 the relay holding circuit with resultant opening of contacts 120 and 121. The solenoid thereupon becomes deenergized, but at this time the actuator lever 27 will be exerting a downward force on the control pin 100 and will hold it frictionally against forward motion by a light-weight return spring 127 which acts normally to hold the controller pin 100 in its forward non-indicating position when the solenoid is deenergized. After the magazine M has been 50 initially set as just described the completed setting will occur as described for the preferred form.

Switch 103 is opened only when the color slide 55 is not subject to constant opening and closing during loom operation. It opens preferably during the first pick of the two-pick cycle and spring 127 moves pin 100 to its normal forward position when the actuator returns to its neutral position, and there is no chance that an indication of weft exhaustion for one two-pick cycle can be carried over into the next cycle.

In the modified form the magazine will be 60 reset essentially the same as in the preferred form except that the resetting operation will be effected by a single down motion of the actuator instead of the two-step motion of the preferred form. In the modified form, as it is true also in the preferred form, bobbin transfer results in forward motion of the weft feeler to a position in which it cannot indicate weft exhaustion.

From the foregoing it will be seen that the invention sets forth simple means by which the usual multicolor weft replenishing mechanism can be modified so as to permit the use of a

positive connection between the shaft 55 and the transerrer latch 49. This positive connection insures greater certainty in the revoking operation and can be used due to the fact that the down motion of the actuator is used to reset the magazine at a time when the lay cannot be in engagement with the transerrer latch.

In the preferred form the preliminary down motion of the actuator 29 effected by decline *a* holds whatever relation the feeler establishes between the actuator lever member and the controller member, this relation depending upon whether the shuttle being detected has ample weft, or requires replenishment, and the completed down motion of the actuator effected by area *c* comes at a time when the magazine can be reset with assurance that the bunter will always be out of engagement with the latch. In the modified form the delay between indication of weft exhaustion and down motion of the actuator is effected by a holding circuit for the relay, and this holding circuit is opened by rocking of the color slide when a replenishing operation is initiated. The cam areas A and A¹ perform the dual function of moving the actuator first to initiate a weft replenishing operation in one two-pick cycle and then resetting the magazine during the next two-pick cycle. As shown herein the shaft 55 is positively connected to both the shuttle feeler 78 and the transerrer latch, but it will be sufficient for the purposes of the invention if the detector and latch are connected in a train of positively acting elements which move to and from transfer position in unison, so long as provision is made for returning the shaft 55 to its normal position after a replenishing operation is called.

Having thus described the invention it will be seen that changes and modifications of the foregoing specific disclosure may be made without departing from the spirit and scope of the invention.

What is claimed as new is:

1. In a weft replenishing loom having a lay, weft replenishing mechanism including a latch normally out of the path of the lay but which is engaged with the lay for a given period during a weft replenishing operation, said replenishing mechanism incident to a replenishing operation having first an initial setting operation on one pick of the loom and second a completed setting operation on the next pick of the loom preparatory to a replenishing operation and third a resetting operation on the third pick of the loom to return the replenishing mechanism to normal condition, a cam effecting said setting and resetting operations rotating in a two-pick cycle and having two areas the first of which at the beginning of said two-pick cycle effects the first setting operation upon indication of weft exhaustion, the second area of the cam effective during the second pick of the cycle to cause the second setting operation of the replenishing mechanism, and said first area during the first pick of the next two-pick cycle effecting the third operation of the mechanism subsequent to said period, to the end that the first setting operation and the resetting operation are both effected by the same area of said cam.

2. In a weft replenishing loom operating with a lay and bobbin transfer mechanism normally disconnected from the lay, a weft feeler capable of indicating weft exhaustion at the beginning of a two-pick cycle of the loom, a cam operating in said two-pick cycle having two areas the first of

which is effective in the first pick of the cycle in the event that the weft feeler indicates weft exhaustion to initiate a replenishing operation and the second area of which during the second pick of the cycle effects movement of the transfer mechanism into position for cooperation with the lay, the transfer mechanism and lay being thereafter normally in engagement for a given period starting near the end of one two-pick cycle and extending into the beginning of the next two-pick cycle, a shuttle detector positively connected to said transfer mechanism to revoke a transferring operation prior to the time when said period can start by moving the transfer mechanism out of position for cooperation with the lay, and mechanism operated by said first area of the cam during said next two-pick cycle subsequent to said period to reset the transfer mechanism to normal position.

3. In a weft replenishing loom having a lay and a transfer latch which when in normal position is out of the path of the lay, a shuttle position detector positively connected to said latch and normally in non-detecting position, 25 weft replenishing mechanism having an initial setting on one pick of the loom incident to indication of weft exhaustion and thereafter having a completed setting on the second pick of the loom to move the latch into the path of the lay and move the detector to shuttle detecting position preparatory to a weft replenishing operation, the latch and lay being operatively connected subsequent to said completed setting for a given period ending when the lay reaches a given point in the rearward movement thereof after a replenishing operation, said detector if engaged by a misplaced shuttle positively moving the latch out of the path of the lay to prevent a replenishing operation, cam means rotating in a two-pick cycle having two areas the first of which in said one pick of the loom effects said initial setting of the replenishing mechanism upon indication of weft exhaustion in the first pick of a two-pick and the second area of which in said second pick of the loom effects said completed setting of the weft replenishing mechanism in the second pick of the cycle, and mechanism causing said first area to be effective in the first pick of the next two-pick cycle subsequent to said period to reset the replenishing mechanism to normal position and effect return of the latch and detector to the normal positions thereof.

4. In a weft replenishing loom in which a lay and bobbin transfer mechanism are mutually engaged during a weft replenishing operation for a period of the lay motion starting during a forward motion of the lay and ending when the lay in the following rearward movement thereof reaches a given point, an actuator mounted for sliding movement on the loom, a cam operating in a two-pick cycle operatively connected to the actuator and having two areas, one area for one pick of the cycle and the other area for the second pick of the cycle, said one area of the cam giving the actuator motions in one direction at regularly recurring two-pick intervals when the lay in the rearward movement thereof is beyond said given point and said other area of the cam giving the actuator other motions in the opposite directions alternating with the first motions and also occurring at two-pick intervals, means dependent upon indication of weft exhaustion cooperating with said actuator when the latter has one of the first mentioned motions thereof initiating a setting of the loom for a weft

13

replenishing operation, said means and actuator cooperating when the latter has one of the second mentioned motions thereof to complete the setting of the loom for a replenishing operation, the lay and latch thereafter being normally mutually engaged for said period, resetting mechanism operated by said actuator when the latter has the next of said first motions thereof following a weft replenishing operation effective to reset the loom, a shuttle position detector, and positively acting connections between said shuttle detector and said transfer mechanism, effective if said shuttle detector is moved by a misplaced shuttle prior to the time when said period can begin to prevent a replenishing operation by moving said bobbin transferring mechanism to inoperative position with respect to the lay by a force transmitted positively through said positively acting connections.

5. In a weft replenishing loom having a lay, a train of positively connected mechanisms including a shuttle position detector in non-detecting position and a transfferer latch out of the path of the lay when said train is in the normal position thereof, actuator means operating regularly in two-pick cycles, moving in one direction during the first pick of each cycle and moving in the opposite direction in the second pick of each cycle and effective upon indication of weft exhaustion and during the second pick of a given two-pick cycle to cause movement of the train to the transfer position thereof in which the detector is in shuttle detecting position and the latch is in the path of the lay preparatory to a weft replenishing operation of the loom, the latch in the event that a weft replenishing operation is completed remaining in engagement with the lay until the latter reaches a given point in the rearward movement thereof immediately after a replenishing operation, the detector in the event of movement thereof by a misplaced shuttle when in transfer position positively moving the latch out of the path of the lay, and mechanism operated by said actuator means during the first pick of the two-pick cycle next following said given two-pick cycle after the lay has passed said given point in the rearward movement thereof subsequent to a replenishing operation to return said train to the normal position thereof.

6. In a weft replenishing loom which when having a completed setting for a replenishing operation moves a shuttle position detector from normal non-detecting position to shuttle detecting position and moves a transfferer latch normally out of the path of the lay into the path of the lay, positively acting connections between the detector and latch moving the latter out of the path of the lay in the event that the detector is moved by a misplaced shuttle, actuator means operating regularly in two-pick cycles, moving in one direction in the first pick of each cycle and in the opposite direction in the second pick of each cycle and effective during the second pick of a given two-pick cycle following a prior indication of weft exhaustion to give the loom said completed setting, and mechanism operated by the actuator means on the first pick of the next two-pick cycle after said given cycle subsequent to disengagement of the lay and latch incident to a replenishing operation to move the detector and latch back to the normal positions thereof.

7. In a weft replenishing loom having a lay and a train of positively connected elements including a shuttle position detector in non-detecting position and a transfferer latch out of the path

14

of the lay when the train is in normal position, said train being movable to transfer position in which the detector is in shuttle detecting position and the latch is in the path of the lay, an actuator operating in a two-pick cycle moving in opposite directions from a neutral position thereof, said actuator when moving in one direction from the neutral position thereof in one pick of the cycle effective upon indication of weft exhaustion to give the loom an initial setting preparatory to a replenishing operation and when moving in the opposite direction from the neutral position thereof in the second pick of the cycle effective to give the loom a completed setting for a replenishing operation and effect movement of said train to the transfer position thereof, and a lost motion connection between said train and actuator enabling the actuator to move in said opposite directions from the neutral position thereof without affecting said train when the latter is in normal position but effecting return of said train from the transfer position to the normal position thereof, provided the loom has been given a completed setting, when the actuator moves in said one direction in the next two-pick cycle thereof.

8. In a weft replenishing loom having a lay and a setting shaft connected to a shuttle position detector and a transfferer latch for movement positively therewith from normal position to transfer position and back to normal position, the detector being in non-detecting position and the latch being out of the path of the lay when the shaft is in normal position and the detector being in shuttle detecting position and the latch being in the path of the lay when the shaft is in transfer position, an actuator operating in a two-pick cycle moving in opposite directions from a neutral position thereof and when moving in one direction from said neutral position in one pick of the cycle effective upon indication of weft exhaustion to give the loom an initial setting preparatory to a weft replenishing operation and when moving in the opposite direction from said neutral position in the next pick of the cycle effective to give said loom a completed setting for a replenishing operation and cause movement of said shaft from the normal to the transfer position thereof, and resetting means operatively interposed between the actuator and the shaft including a lost motion connection whereby said actuator can have said opposite motions thereof from said neutral position without operative effect on the shaft so long as the latter is in the normal position thereof but effective when said shaft is in the transfer position thereof and said actuator has said one motion thereof in the next two-pick cycle thereof to return the setting shaft to normal position.

9. In a weft replenishing loom having a lay and a transfferer latch which incident to a weft replenishing operation is in engagement with the lay until the latter reaches a given point in the rearward motion thereof immediately following a replenishing operation, a train of positively connected mechanisms including a shuttle position detector and said transfferer latch, the detector being in non-detecting position and the latch being out of the path of the lay when the train is in normal position, a weft feeler detecting the condition of weft when the lay is on front center at the beginning of a regularly recurring two-pick cycle of the loom, an actuator lever member, a controller member for the lever member under control of the feeler, the latter when indicating

weft exhaustion causing said controller member to be in the path of the lever member and the feeler when indicating presence of ample weft causing the controller member to be out of the path of the lever member, a cam rotating once in each of said two-pick cycles having one area for one pick and a second area for the second pick of each cycle, said one area having a step effecting a preliminary motion of the lever member at the beginning of each two-pick cycle to move the lever member to a position in which the controller member is unable to be in the lever member path if the feeler indicates presence of ample weft, the controller member being in the path of the lever member when the latter has said preliminary motion if the feeler indicates weft exhaustion, said one area having a dwell holding the lever member against motion subsequent to said preliminary motion thereof until the lay in the backward movement thereof reaches said given point, and said one area having another step effective after the lay passes said given point to give the lever member an additional motion effective, in the event the feeler indicates weft exhaustion, to give the loom an initial setting preparatory to a replenishing operation, said second area of the cam in the second pick of the cycle effecting a completed setting of the loom for a replenishing operation by moving said train to move the detector to shuttle detecting position and move the latch into the path of the lay, and said other step of said one area in the next two-pick cycle effecting resetting of said train to normal position, the detector if moved by a misplaced shuttle after said completed setting moving said train to move the latch out of the path of the lay by a force transmitted positively through said train.

10. In a weft replenishing loom having a lay and a shuttle position detector normally in non-detecting position and a transerrer latch normally out of the path of the lay, positively acting connections between the detector and the latch causing the detector and latch to move in unison from the normal position thereof to transfer position in which the detector is in shuttle detecting position and the latch is in the path of the lay and return in unison to normal position, weft replenishing mechanism which incident to a replenishing operation has initial setting, completed setting and resetting operations, actuator means for the replenishing mechanism, a cam rotating in a two-pick cycle operatively connected to the actuator means, a weft feeler indicating weft exhaustion at the beginning of said two-pick cycle when the lay is on front center, the lay and latch subsequent to said completed setting of the replenishing mechanism being in engagement with each other until the lay in rearward motion thereof immediately following a replenishing operation reaches a given point, said cam during the first pick of said cycle giving the actuator means a preliminary motion to hold the indication of the weft feeler and thereafter holding the actuator means stationary until the lay in the rearward movement thereof after indication of weft exhaustion reaches said point and the cam thereafter giving said actuator means a completed motion to effect initial setting of the replenishing mechanism, said detector if moved by a misplaced shuttle subsequent to said completed setting acting through said positively acting connections to move the latch out of the path of the lay, and mechanism operated by said actuator means when the latter is given a

completed motion in the next two-pick cycle of the cam effecting resetting of the loom and return of the detector and latch to the normal positions thereof.

5 11. In a weft replenishing loom having a lay, a cam rotating in a two-pick cycle, an electrically indicating weft feeler indicating exhaustion at the beginning of said two-pick cycle when the lay is on front center, a transerrer latch, a shuttle position detector positively connected to the latch, electric holding circuit means retaining the indication of the weft feeler until the lay in the rearward movement thereof subsequent to indication of weft exhaustion reaches a point at which the lay is incapable of engagement with the latch, said cam in the first pick of the cycle after the lay on the rearward movement thereof has passed said point effective due to retention of said indication of weft exhaustion 10 to cause an initial setting of the loom for a replenishing operation, and said cam on the second pick of the cycle completing the setting of the loom for a replenishing operation, means effective incident to the initial setting of the loom 15 opening said holding circuit, said loom when in the completed setting thereof having the shuttle position detector in detecting position and a transerrer latch in the path of the lay, the detector if engaged by a misplaced shuttle positively moving the latch out of the path of the lay, and said cam in the second two-pick cycle 20 thereof after the lay passes said point effecting resetting of the loom including movement of the latch out of the path of the lay.

25 12. In a weft replenishing loom having a lay and a transerrer latch, a cam rotating in a two-pick cycle, an electrically indicating weft detector giving indication of weft exhaustion when the lay is on front center at the beginning of said two-pick cycle, a color slide rockable in opposite directions from the normal position thereof operatively connected to the cam, the latch and lay being mutually engaged incident to a weft replenishing operation and becoming disengaged from each other subsequent to a replenishing operation when the lay in the backward movement thereof reaches a given point, holding circuit means retaining the indication given by the feeler until after the lay passes said point in the rearward movement thereof, said cam having an area effective in the first pick of the cycle after the lay passes said point to give the color slide a rocking movement in one direction to give the loom an initial setting for a replenishing operation, means operated by the color slide when the latter has said rocking movement in one direction opening the holding circuit means, said cam in the second pick of the cycle effective to rock the color slide in the opposite direction to give the loom a completed setting for a replenishing operation, and said cam in the first pick of the next two-pick cycle effecting resetting of the loom by said area of the cam.

30 13. In a weft replenishing loom operating in a two-pick cycle beginning when indication of weft exhaustion is given and having a lay which on a replenishing operation remains in engagement with a transerrer latch for a given period, the lay being at a given point in the backward motion thereof at the end of said period, an electric detecting circuit closed upon indication of weft exhaustion at the beginning of said two-pick cycle when the lay is on front center, an electric holding circuit closed upon closure of the detecting circuit, a solenoid circuit closed

as long as the holding circuit is closed, a color slide operatively connected to the cam, said cam having an area cooperating with said color slide after the lay reaches said point and dependent upon closure of the solenoid circuit to effect an initial setting of the loom for a weft replenishing operation, and means effective incident to movement of the color slide opening said holding circuit, said cam in the second pick of the cycle cooperating with the color slide to effect a complete setting of the loom for a replenishing operation, and said cam effective through said area thereof in the next two-pick cycle thereof effecting resetting of the loom after said period.

14. In a weft replenishing loom in which a weft replenishing operation occurs in a two-pick cycle, a setting shaft movable from the normal position thereof to transfer position to set the loom for a replenishing operation, an arm secured to and moving with said shaft, an actuator having a range of movement in a two-pick cycle effective in the first pick of the cycle while in one part of said range of movement to effect an initial setting of the loom for a replenishing operation in the event of indication

15 20 25

of weft exhaustion and effective in the second pick of the cycle while in another part of said range of movement to move said shaft from the normal position thereof to the transfer position thereof, and lost motion resetting connections between said actuator and shaft enabling said actuator to move throughout said range of movement without affecting said shaft when the latter is in the normal position thereof and effective when the shaft is in the transfer position thereof and said actuator moves in said one part of said range of movement to cooperate with said arm to return said shaft to the normal position thereof.
